UNITED STATES PATENT OFFICE.

ALFRED EDWARD FISHER, OF OSHAWA, ONTARIO, CANADA.

GRAMOPHONE REPEATING DEVICE.

Application filed July 18, 1922. Serial No. 575,792.

To all whom it may concern:

Be it known that I, ALFRED EDWARD FISHER, of the town of Oshawa, in the county of Ontario, in the Province of Ontario, Canada, have invented certain new and useful Improvements in Gramophone Repeating Devices, of which the following is the specification.

My invention relates to improvements in gramophone repeating devices and the object of the invention is to devise a simple and effective attachment which will cause the sound box and needle to be automatically swung over into its initial position when it has reached the end of the record.

A further object is to devise a repeating device which can be adjusted to work with records of different sizes and a still further object is to devise a repeating device which will be silent in operation.

My invention consists of a repeating device constructed and arranged all as herein-after more particularly described and illustrated in the accompanying drawing in which:

Fig. 1 represents a plan view of the record table, sound box and tone arm showing my device applied thereto.

Fig. 2 is a side elevation thereof showing the needle engaging the record and a portion of my device mounted on the sound box in the inoperative position, and

Fig. 3 is a similar view to Figure 2 showing a portion of my device on the sound box in the operative position.

Like characters of reference indicate corresponding parts in the different views.

1 is the record turntable to which is removably secured the usual central spindle 2 adapted to be rotated in the usual manner. 3 is the sound box. 4 is the tone arm. 5 is the annular plate in the case of the gramophone through which the tone arm 4 extends.

45 51 is a bracket member suitably secured to the back face of the sound box and having pivoted to its lower end the arm 6 upon the free end of which is journalled the wheel 7 which is preferably rubber-tired. 8 is a 50 shoulder on the upper end of the arm 6 adapted to engage a corresponding shoulder 9 on the lower end of the bracket member 51 when the arm is swung into the position illustrated in Figure 3.

55 10 is a spring secured at one end to the bracket 51 and at the other end to the arm

6. 11 is a projection on the free end of the arm 6.

12 is the needle mounted in the usual manner in the socket 13 on the sound box.

14 is a hood member adapted to extend over the spindle 2 above the record 15 and to be secured thereto by means of the set-screw 16. 17 is an arm extending transversely through the hood 14 above the spindle 2 and adapted to be adjustably secured in position therein by means of the set-screw 18.

19 is an arm adjustably secured at one end to the plate 5 by means of the headed stud 20 on such plate which extends through a slot

21 in the arm 19. 22 is a thumb screw journalled in the bearing 23 on the top of the machine and held against displacement by the collars 24. 25 is a lug on the held end of

the arm 19 said lug being provided with the threaded orifice 26 adapted to receive the screw 22. The free end of the arm is bent

inwardly towards the spindle 2 and provided with a hooked member 27 pivoted thereto, one end of the hooked member 27

being provided with the buffer 28 and a spring 29 extending between the arm 19 and the hooked member 27 for normally holding

the same in the required position.

My device operates as follows:

When the record is placed on the turntable and the latter rotated the sound box travels across the same in an inward direction in the usual manner until the end of the record is reached, when upon the arm 17 being suitably adjusted in the hood 14, such arm will strike the projection 11 on the

arm 6, causing such arm and wheel 7 to be swung downwardly into the position illustrated in Figure 3 wherein the wheel 7 will

engage the record 15 and the needle will be raised off such record. Owing to centrifugal force the sound box when supported on the wheel which engages the record will be

swung to its outermost position wherein a buffer 30, provided on the forward face of the sound box, will engage the buffer 28, thus

swinging the hooked end of the hooked member 27 into engagement with the arm 6

swinging the latter into the inoperative position illustrated in Figure 2. The spring

10, which is distended when the arm 6 is moved into the position illustrated in Figure

3, will restore the arm to the position illustrated in Figure 2 when such arm is moved

by the hooked member over the vertical cen-

tre line thus allowing the sound box to drop down until the needle engages the record. On desiring to adjust the arm 19 to suit records of different sizes, it is merely necessary to rotate the thumb screw 22, which moves the arm through the medium of the lug 25 thereon into which the screw is threaded.

From the above description it will be seen that I have devised a simple and effective gramophone repeating device which can be readily applied to existing gramophones and which will be positive in use and moreover can be adjusted to operate on records of different sizes.

What I claim as my invention is.

1. In a gramophone repeating device, the combination with the sound box and record, of a bracket secured to the sound box, an arm pivotally mounted on the bracket, a wheel journaled on the free end of the arm, the wheel engaging the record upon the arm being swung into the operative position and elevating the sound box with the consequent disengagement of the needle from the record, a shoulder on the bracket and a shoulder on the arm engaging each other upon the arm being swung into the operative position.

2. In a gramophone repeating device, the combination with the sound box and record, of a bracket secured to the sound box, an arm pivotally mounted on the bracket, a wheel journaled on the free end of the arm, the wheel engaging the record upon the arm being swung into the operative position and elevating the sound box with the consequent disengagement of the needle from the record, a shoulder on the bracket and a shoulder on the arm engaging each other upon the arm being swung into the operative position and a spring secured to the bracket and its other end secured to the arm for normally retaining it in the upper or inoperative position.

3. In a gramophone repeating device, the combination with the sound box and record, of a swingable arm pivoted to the sound box, a rotatable member on the free end of said swingable arm adapted to engage the record upon being thrown into the operative position and lift the needle out of engagement therewith by raising the sound box, a projection on the arm, means engaging the projection for swinging the arm into the operative position and means engaging the arm for swinging it into the inoperative position.

4. In a gramophone repeating device, the

combination with the sound box, record turn table spindle and record, of a swingable arm pivoted to the sound box, a rotatable member on the free end of said swingable arm adapted to engage the record upon being thrown into the operative position and lift the needle out of engagement therewith by raising the sound box, a projection on the arm, an adjustable arm on the record turn table spindle adapted to engage the projection upon the sound box reaching the inner end of its run and a suitably supported hook member engaging the arm upon the sound box reaching the outer limit of its run.

5. In a gramophone repeating device, the combination with the sound box, record turn table spindle and record, of a swingable arm pivoted to the sound box, a rotatable member on the free end of said swingable arm adapted to engage the record upon being thrown into the operative position and lift the needle out of engagement therewith by raising the sound box, a projection on the arm, an adjustable arm on the record turn table spindle adapted to engage the projection upon the sound box reaching the inner end of its run and a suitably supported adjustable hook member engaging the arm upon the sound box reaching the outer limit of its run.

6. In a gramophone repeating device, the combination with the sound box, record turn table spindle and record, of needle disengaging means and a hood adapted to be secured to the top of the record turn table spindle, an arm adjustably secured to the hood adapted to engage the needle disengaging means for throwing the same into the operative position and an adjustably mounted arm having a hook shaped member adapted to engage the needle disengaging means and throwing it into the inoperative position, a buffer on the sound box adapted to engage the buffer on the hook member for actuating the same.

7. In a gramophone repeating device, the combination with the sound box, record turn table spindle and record, of needle disengaging means on the sound box, a buffer on the sound box, an adjustable arm, a spring-held hook member mounted on the adjustable arm, a buffer on the hook member, said buffer on the sound box adapted to engage therewith.

ALFRED EDWARD FISHER.
